FUSE CUTOUT

Andrew W. Edwards, East McKeesport, Pa., assignor to Westinghouse Electric Corporation, East Pittsburgh, Pa., a corporation of Pennsylvania

Application June 23, 1949, Serial No. 100,868

9 Claims. (Cl. 200—117)

1

This invention relates to electrical protective devices and more especially to circuit interrupters of the tensioned fuse type for electrical systems.

An outstanding general object of this invention is the provision of a simple and reliable cutout of the tensioned fuse type which is well suited for arresting the flow of overload current in an electrical power transmission line.

Another object of this invention is that of providing a tensioned fuse cutout in which the fuse link thereof is easily inserted or removed and is effectively supported in the conductive position.

A further object of this invention is the provision of a strong and mechanically simple fuse cutout which affords physically stable support for the fuse link thereof when operating under normal current conditions, and which promptly snaps to circuit interrupting position upon encountering excessive current across the link.

Another object of the present invention is the provision of a tensioned fuse cutout which is easily constructed, and is highly satisfactory when installed.

A still further object of this invention is that of providing an inexpensive and practical tensioned fuse cutout such as may be installed on power transmission line poles, towers, transformers, or the like.

Another object of this invention is the provision of a satisfactorily electrically conductive tensioned fuse cutout.

A further object of the present invention is that of providing simple and readily produced tensioning means for a tensioned fuse cutout.

From the standpoint of function, tensioned fuse cutouts are intended to arrest the flow of current by spending a fusible electrically conductive or heat-sensitive portion in response to overload current, thereupon opening a related electrical line with a snap action. A variety of these cutouts employ contact arms, which support a fuse link including the fusible portion and are biased in favor of pulling the leads of the fuse apart when fusion occurs, thus to extend the opening of the transmission line circuit and decrease the danger of arcing. To restore the cutout to electrically conductive position in the power line, a replacement fuse of desired rating is tensioned between the contact arms, and this remains in tension until current overload is encountered to release the bias of the arms in favor of separation as already described.

Tensioned fuse cutouts have come into demand in such important fields as the outdoor transmission of electrical power, and are often used on

line towers, poles, transformers, or the like, thus to afford a protective component of the power transmission system. Among these systems are those employed for rural electrification, which are mentioned here as an example illustrating certain conditions and economic levels of use of the cutouts. Then, too, it will be appreciated that the quantity of cutouts needed in a particular system may be quite large and that their unit cost accordingly becomes a highly important factor.

There are quite a number of heretofore known circuit interrupters or tensioned fuse cutouts which involve such considerations as failure to lend themselves readily to mass production techniques. In certain instances many of the parts employed for making the cutouts are difficult to produce and assemble, and even then sometimes are instrumental to poor quality and inferior performance of the resulting product. In producing the cutouts, it is frequently advantageous to weld together adjacent parts which are to convey the line current, but the very shape or arrangement of these parts often makes welding or other forms of assembly a very time-consuming operation. A variety of cutouts include contact arms and biasing springs made of wire and these arms usually take the form of trusses to afford strength, but arms of this sort usually are unwieldy to produce and assemble.

There are heretofore known cutouts, too, which once installed, offer an extremely unfavorable aspect of upkeep. In this connection, it will be appreciated that certain of these cutouts, because of the precise character and arrangement of their parts, are very tedious to reset or service from a safe distance with a suitable tool as in replacing a spent fuse. The contact arms and biasing means in these devices so often have extremely poor lateral stability and thus are troublesome to reset to operating position with a tool. At times, this fallacy adds to the occupational hazards of linemen who, for example, service the cutouts from a selected position on a transmission line pole or tower under conditions which are already adverse to absolute safety.

A further object of this invention accordingly is the provision of a practical and reliable tensioned fuse cutout which is easy to produce and simple to service and maintain.

A still further object of the present invention is that of providing a strong and easy to assemble tensioned fuse cutout having simplicity of structure, a well directed biasing action and good lateral stability of the contact arms.

2

The preceding objects and other objects of this invention will become more apparent upon consideration of the following description of certain preferred embodiments thereof, when taken in connection with the accompanying drawing, in which:

Figure 1 represents in side elevation, a tensioned fuse cutout having features in accordance with the invention;

Fig. 2 is a top plan view depicting details of the apparatus noted in Fig. 1;

Fig. 3 is a fragmentary plan view of the lower contact arm of the apparatus in Fig. 1;

Fig. 4 is a perspective view representing in detail a terminal component of the apparatus in Fig. 1; and

Fig. 5 is a fragmentary plan view of a modified form of the apparatus in Fig. 3.

In the particular embodiment of the invention disclosed in the accompanying drawing (Figs. 1 to 4 inclusive), there is provided a tensioned fuse cutout 10 which comprises an electrical insulator 11 and relatively movable contact arms 12 and 13 supporting a fuse link 14 which electrically interconnects these arms.

The cutout 10 further includes line terminals 16 and 17 individually corresponding to the contact arms 12 and 13, respectively, for connection of the cutout into a power line of an electrical transmission system. Terminals 16 and 17 are in electrically conductive relation with each other through the fuse link 14 and fusible portion 34 of the latter, so long as the fuse link remains conductive. The relatively movable contact arms 12 and 13 serve to impose tension on the fuse link 14 and separate the free ends of the fusible portion 34 when this is melted or softened by heat of an overload current in the power transmission line. In order to tension the link 14, the contact arm 12 includes electrically conductive spring means 15 having features which will be explained more fully hereinafter. This spring means 15 in effect affords a pivot for displacement of contact arm 12 relative to arm 13. The contact arm 13 preferably is substantially fixed in position relative to the insulator 11.

The insulator 11 illustratively is oblong in shape as for mounting with the major axis in the upright position, and conveniently is round or substantially circular in transverse section. It is made of porcelain, glass, or of any other suitable dielectric. The long dimension of the insulator 11 is useful for giving an effective spacing of the inner ends of the contact arms 12 and 13 which is desired to keep the electrical transmission line open after the fuse link 14 is expended.

Contact arm 13 is made of electrically conductive material such as cobalt-beryllium-copper alloy or copper-clad steel, and advantageously is in the form of a substantially rigid metal strip having the larger dimension of its transverse cross-section substantially lateral to the longitudinal axis of the insulator 11 and substantially lateral to the desired direction of support of fuse link 14. At the outer end remote from the insulator 11, the contact arm 13 conveniently is longitudinally split, and the resulting portions turned or bent back to give integral hooks 13b and 13c on opposite sides of this arm for receiving and holding the fuse link 14. Each of the hooks preferably extends backward and in the backward position diverges from the adjacent edge of the main body of the related contact arm. An outer portion 13a of the contact arm 13, including the hooks, is preferably inclined from the

plane of a rearward portion 13d and toward the outer end of contact 12, thus to enhance the receiving and holding effect on fuse link 14.

At the inner end adjacent to the insulator 11, contact arm 13 preferably is bent away from its corresponding support 19 to provide the terminal 17, this having an opening 17a for receiving a power line fastening device 17b. The fastening device 17b illustratively is a bolt and corresponding nut, the bolt having its shank inserted through opening 17a and welded at the head to the adjacent terminal portion of contact arm 13 so as to assure adequate electrical conductivity at this point. For the sake of ease of production and for affording a continuous electrical path, the contact arm 13 advantageously is one continuous integral strip inclusive of the hooks 13b and 13c.

Support 19, for example, is a substantially rigid metal strip fixed to a corresponding end portion 11c of the insulator 11, the long dimension of the transverse cross section of this strip being substantially lateral to the longitudinal axis of the insulator. The insulator end portion 11c illustratively has a transverse opening into which the support 19 is inserted and cemented in place.

A bolt 22 conveniently extends through aligned openings in the contact arm 13 and support 19 to fasten these portions together as with the aid of a corresponding nut 23. Contact arm 13 and support 19 thus, for example, are held together flat-face to flat-face, the bolt 22 being disposed outward of the bent-away portion of this arm including the terminal 17. Also, the bolt 22 is preferably received in the corresponding opening in support 19 at a point sufficiently far out from the insulator end portion 11c to hold the contact arm 13 and terminal 17 clear of the insulator body. If desired, several bolts, such as the bolts 22, may be employed for fastening together the contact arm 13 and support 19. Usually, though, one bolt is adequate and savings in material thus can be had, especially with the aid of an interlock 27 in which, for example, a protuberance such as pressed tip 27a associated with the arm 13 rests in a slot 27b in the support 19 to prevent relative rotation of the arm and support about the single bolt 22. As an alternative, it will be appreciated that in certain instances the contact arm 13 and the related support 19 may be welded together.

The contact arm 12 illustratively has an outer portion 26, joined as by riveting and welding to the spring biasing means 15 thereof. This outer portion 26, for example, is made of a substantially rigid strip of electrically conductive material such as copper alloy or copper-clad steel. At the outer end, the portion 26 is provided with means for receiving and holding the fuse link 14, such as hooks 26c and 26d in zone 26a which is inclined from the plane of a rearward zone 26b and toward the outer end of contact arm 13, thus to enhance the receiving and holding effect on fuse link 14. The hooks 26c and 26d conveniently are formed by longitudinally splitting the outer end of portion 26 and turning or bending back the split portions in substantially the same plane as zone 26a. Hooks 26c and 26d, in the backward position, preferably diverge from the adjacent sides of the main body of portion 26 for easier admission of the fuse link 14 and better contact therewith.

The biasing spring means 15 (Fig. 3) advantageously includes a main portion 15a and extension portions 15b and 15c and is of electrical-

ly conductive material. A considerable advantage is had by making the spring means 15 from sheet metal or the like, both from the standpoint of production and effective performance in the cutout 10. Thus, for example, in producing the spring means a flat sheet of spring copper alloy metal or other electrically conductive material of suitable spring quality is subjected to a die stamping or cutting operation to give a bifurcated metal blank including the main portion 15a and the extension portions 15b and 15c. The blank so produced illustratively is a substantially Y-shaped piece (Fig. 3) wherein the extension portions 15b and 15c are, for example, substantially parallel and spaced apart to produce a gap therebetween which is somewhat wider than the width of the main portion 15a. Following the stamping or cutting operations, the main portion 15a, for example, is subjected on the flat sides thereof to a rolling or shaping procedure, this usually beginning at the point of bifurcation and going outward along the main portion 15a to render the spring means intermediately convolute at zone 15d (Fig. 3). In certain instances instead of actually rolling or deforming the metal blank to produce the convolute zone 15d, the main portion 15a is merely wound one or more turns in the proper direction through the space between extension portions 15c and 15d and is assembled in the cutout 10 to give the desired bias.

For connecting the contact arm 12 with the insulator 11, there is, for example, a support 18, this illustratively being a substantially rigid metal strip having the inner end thereof introduced in a transverse opening in the insulator end portion 11c and cemented in place. This support conveniently is a straight rigid piece having the longer dimensions of its transverse cross section substantially lateral to the longitudinal axis of the insulator 11. An angular terminal 16 of the contact arm 12 has a leg 16a to which the free ends of extension portions 15b and 15c of the spring biasing means are conveniently secured. For this purpose, the angular terminal 16 is provided with opposed slots 16c and 16d at the apex of the angle thereof for individually receiving the corresponding extension portions 15b and 15c and admitting the same to the underneath side of leg 16a. The extension portions 15b and 15c conveniently are welded to the underneath side of leg 16a of the terminal 16. An opening 16e extends through leg 16a, such as between the points of welding the portions 15b and 15c, and receives a bolt 20 (Fig. 1) which passes through a corresponding opening in support 18 thus to fasten the several elements together with the aid of a nut 21. Leg 16b of the angular terminal 16 illustratively is at about right angles to the leg 16a and conveniently affords edges along the slots 16c and 16d which give cantilever support of the contact arm 12, and more especially of the extension portions 15b and 15c thereof. A connector 16f on the terminal 16, illustratively comprising a bolt and nut, with the bolt extending through an opening 16g in the leg 16b and welded thereto at the head, receives a corresponding end of the power transmission line. The terminal 16, as mounted, preferably is substantially clear of the insulator end portion 11b and away from the spring biasing means 15 and outer portion 26 of the contact arm 12.

Main portion 15a of the spring biasing means 15 illustratively overlaps the outer portion 26

of contact arm 12 and the overlapping portions are riveted and welded together. The outer portion 26 preferably extends outward in the same general direction from the insulator as does the main portion 15a of the spring means 15. By producing welded joints in the contact arm 12, as between the angular terminal 16 and extension portions 15b and 15c, and as between main portions 15a and outer portion 26, an electrically continuous member is successfully assured. It will be appreciated, of course, that in certain instances the spring biasing means 15 and outer portion 26 of the contact arm, inclusive of the hooks 26c and 26d, are made of a continuous piece of strip material or the like as by stamping, cutting and working to desired shape from a single piece of electrically conductive spring quality material, thereby achieving physical and electrical continuity.

20 A bracket 25 illustratively serves for mounting the insulator 11 as in upright position on a pole, line tower or transformer casing, and preferably in disposed at some point in the general vicinity of about half-way between the terminals 16 and 17 or their supports 18 and 19. The inner end of the bracket 25 preferably is of a form which connects to only one side of the transverse periphery of the insulator body, this connection, for example, being on the side directly opposite from those portions of the fuse cutout 10 which are electrically conductive in the power transmission line. The bracket 25 illustratively is a piece of rigid metal strip having one or more openings 25a therethrough, clear of the insulator body for receiving a screw, bolt, or the like to support the cutout 10 in useful position. The inner end of the strap or bar conveniently is affixed to the insulator 11 by being embedded therein or seated in a transverse opening in the side of the insulator body and cemented in. It will, of course, be understood that collars or bands of metal may under certain circumstances be employed for holding the bracket 25 or contact arms 12 and 13 to the insulator body, but this arrangement usually is not preferred, especially where the bracket is susceptible to easy connection with the line complete to ground as by birds roosting on the cutout 10. By keeping the bracket 25 entirely to one side of the insulator 11 and disposing the contact arms 12 and 13 as well as their supports 18 and 19 entirely to the opposite side, so as to be remote from this bracket, danger of line to ground connection between the several elements is successfully reduced.

55 The specific form of insulator 11 and the manner in which bracket 25 and supports 18 and 19 are mounted and arranged thereon form no part of this invention, but comprise the invention of James M. Wallace and Earl F. Beach, and are more particularly described and claimed in their copending application Serial No. 98,378, on Open Link Cutouts, filed June 10, 1949, and assigned to the same assignee of this invention.

60 The contact arms 12 and 13 illustratively have their respective longitudinal center lines in about the same plane as the longitudinal axis of the insulator 11 and are laterally strong by virtue of their effective widths in this direction and the form of the spring biasing means 15. For interconnecting these arms, the fuse link 14 preferably includes an opposed pair of electrical conductors 32 made, for example, of copper wire and provided at their outer ends with eyes 33. The inner ends of the electrical conductors 32 are spaced apart to form a gap, and located in

this gap and connecting the conductors 32 is the fusible element 34 of relatively low melting point material. This fusible element 34 and the inner ends of conductors 32 preferably are enclosed within a tube 35 made, for example, of a weather-protective compound such as phenolic resin 29 lined with fiber 31, or a like material which is capable of emitting an arc-suppressing gas when in proximity to an electric arc. Preferably a cap 30 is secured to the upper end of tube 35 and to the conductor 32 which passes through the cap. On the eyes 33 and located immediately adjacent to the inner sides thereof and joined to the conductors 32, are electrically conductive buttons or stops 33a for pressing against the outside surfaces of contact arms 12 and 13.

In use of the cutout 10, one of the opposed electrical conductors 32 of the fusible link 14 is set into the hook 13c or 13d of contact arm 12 with the corresponding stop 33a on that side of this arm which is remote from the arm 13. For this, a conventional switch stick is useful to handle an appropriate one of the eyes 33. With further use of the switch stick or tool, conductor 32 at the opposite end of the link 14 is set into either hook 13b or 13c of contact arm 13 with the corresponding stop 33a outside this arm. In the latter operation, the contact arm 12 is pulled against the bias of spring biasing means 15 toward the fixed arm 13. Stops 33a once seated comprehend the contact arms 12 and 13, while the link 14 is in tension under the bias of arm 12. The outer ends 13a and 26a of the contact arms in being inclined and substantially approaching each other, advantageously maintain the bottoms of the hooks 13b and 13c toward the bottom of the opposed hooks 26c and 26d and thus make contact at more than one point. Then with normal current conditions prevailing, the fuse cutout 10 serves to maintain current flow through the transmission line of which terminal 16 and the corresponding contact arm 12, fuse link 14, an contact arm 13 and the corresponding terminal 17 comprise a part. If, however, overload currents pass through the electrically conductive portions just named, the fusible element 34 in the link 14 ruptures or melts. When that occurs, contact arm 12 swings (clockwise in Fig. 1) with a snap under the force of the spring biasing means 15 thereof, quickly pulling apart the electrical conductors 32 of the link 14. Current flow thus no longer prevails across the cutout 10, but can be restored and maintained if safe transmission limits exist, by introducing another link 14 having a fusible component 34 of appropriate current rating.

Where, for example, the cutout 10 is to be used for lending safety to a high voltage electrical transmission line, as is often the case, a considerable benefit is had by employing an insulator 11 having integral skirts 11a spaced along the length of the insulator body. These skirts tend to arrest corona discharge between the terminals 16 and 17. The mounting bracket 25 conveniently is secured to the insulator 11 at a point intermediate the plurality of skirts 11a which then also protect this element against discharge.

A somewhat modified form of spring biasing means 15 which is used in accordance with the present invention is represented in Fig. 5 of the accompanying drawing. In this particular embodiment of the spring means 15, a convolute portion is provided comprising two coils 15f and 15g respectively made by rolling or winding extension portions 15b and 15c on opposite sides of

main portion 15a, for example, by beginning with an electrically conductive metal blank of the character described in connection with production of the single coil biasing unit represented in Fig. 3. It will be understood that the modified form of biasing means conveniently is disposed in the cutout 10 in substantially the same manner as the single coil biasing means to serve in lieu of the latter.

10 Thus it will be seen that in this invention there is provided a tension fused cutout and apparatus for the same in which the various objects noted herein, together with many thoroughly practical advantages, are successfully achieved. It will be seen that the cutout is simple and is effectively biased in favor of snapping to open circuit position upon overload conditions being encountered. Also, it will be seen that the cutout can be readily produced and is easy to service.

20 Having described certain preferred embodiments of the invention in accordance with the patent statutes, it is desired that the invention be not limited to this particular construction, inasmuch as it will be obvious to persons skilled in the art that many modifications and changes may be made in this particular structure without departing from the broad spirit and scope of this invention. Accordingly, it is desired that the invention be interpreted as broadly as possible and that it be limited only as required by the prior art.

I claim as my invention:

35 1. A fuse cutout comprising an electrical insulator, spaced electrically conductive contact arms extending from connection with the insulator and having their outer ends suited for receiving and holding a fuse link, one of said arms including an intermediately convolute electrically conductive flat spring member which is split at its inner end to provide spaced integral extension portions toward the insulator for mounting thereon, and a single integral main portion extending outward for urging the link receiving and holding end of the arm away from the corresponding end of the other arm.

40 2. A fuse cutout comprising an electrical insulator, spaced electrically conductive contact arms extending from connection with the insulator and having their outer ends suited for receiving and holding a fuse link, one of said arms being substantially fixed in position and the other of said arms including a spring strip having spaced extension portions toward the insulator and a main portion coiled into a spring 45 between said extension portions and reaching outward for urging the link receiving and holding end of the arm away from the corresponding end of the substantially fixed arm.

55 3. A fuse cutout comprising an electrical insulator, spaced electrically conductive contact arms extending from connection with the insulator and having their outer ends suited for receiving and holding a fuse link, one of said arms being substantially fixed in position and the other of said arms including a conductive spring strip having spaced individually wound convolute extension portions toward the insulator and a main portion integral with and between the extension portions, said main portion being of less width than the gap between said extension portions and reaching outward for urging the link receiving and holding end of the arm away from the corresponding end of the substantially fixed arm.

70 4. A fuse cutout comprising an elongated elec-

trical insulator, a bracket connected with an intermediate portion of said insulator for supporting the insulator body, spaced electrically conductive contact arms extending transversely outward from connection with the opposite end portions of the insulator and suited for receiving and holding a fuse link at their outer ends, one of said arms being of flat strip material comprising an inner portion formed as an intermediately convolute spring strip which is split at its inner end to provide spaced extension portions toward the corresponding insulator end for mounting thereon, and a single main portion extending outward for urging the outer link receiving and holding end of the arm away from the corresponding end of the other arm.

5. A fuse cutout comprising an elongated electrical insulator, spaced electrically conductive contact arms extending transversely outward from connection with the opposite end portions of the insulator and having their outer ends suited for receiving and holding a fuse link, one of said arms being substantially fixed in position and the other of said arms being substantially flat in transverse cross section with the longer sides of the cross section substantially lateral to the intended position of the fuse link, for rigidity in this direction, and said substantially flat arm including a spring strip having spaced extension portions toward the corresponding insulator end and a main portion coiled into a spring between said extension portions and reaching outward for urging the link receiving and holding end of the arm away from the corresponding end of the substantially fixed arm.

6. A fuse cutout comprising an elongated electrical insulator, spaced electrically conductive contact arms extending transversely outward from connection with the opposite end portions of the insulator and having their outer ends suited for receiving and holding a fuse link, one of said arms being substantially fixed in position and the other of said arms being substantially flat in transverse cross section with the longer sides of the cross section substantially lateral to the intended position of the fuse link, for rigidity in this direction, and said substantially flat arm including a conductive spring strip having spaced

individually wound convolute extension portions toward the corresponding insulator end and a main portion integral therewith and between the extension portions, said main portion being of less width than the gap between said extension portions and reaching outward for urging the link receiving and holding end of the arm away from the corresponding end of the substantially fixed arm.

10 7. A contact arm for the fuse link of a tensioned fuse cutout, said arm comprising electrically conductive spring strip means having a main portion, and integral extension portions reaching from said main portion and forming a gap between each other greater than the width of the latter, and said spring strip means being convolute intermediate the length thereof.

15 8. A contact arm for the fuse link of a tensioned fuse cutout, said arm comprising an electrically conductive spring strip having a main portion, and extension portions reaching from said main portion and forming a gap between each other greater than the width of the latter, and said main portion being wound between said extension legs to provide a coil.

20 9. A contact arm for the fuse link of a tensioned fuse cutout, said arm comprising an electrically conductive spring strip having a main portion, and integral extension portions reaching from said main portion and forming a gap between each other greater than the width of the latter, and said extension portions being individually wound beside the main portion to provide coils.
